ATTORNEY

UNITED STATES PATENT OFFICE.

JOHN LYALL BROWN, OF VERONA, PENNSYLVANIA, ASSIGNOR TO WESTINGHOUSE ELECTRIC & MANUFACTURING COMPANY, A CORPORATION OF PENNSYLVANIA.

SHORT-CIRCUITING DEVICE.

Application filed October 15, 1923. Serial No. 668,467.

To all whom it may concern:

Be it known that I, JOHN LYALL BROWN, a citizen of the United States, and a resident of Verona, in the county of Allegheny and State of Pennsylvania, have invented a new and useful Improvement in Short-Circuiting Devices, of which the following is a specification.

My invention relates to short-circuiting devices or other speed responsive devices particularly adapted for electric machines, and it has particular relation to centrifugally-operated mechanisms for effecting a repulsion operation of a machine during the starting and an induction operation during the normal operating period.

My invention has for one of its objects to provide a simple, practical and relatively inexpensive device of the above character, wherein a plurality of members are simultaneously actuated centrifugally in a direction transverse to the axis of rotation, and concurrently in an axial direction to operate the short-circuiting means into engagement with the end of the commutator cylinder.

In the accompanying drawing,

Figure 1 is a front view of the device, in section on the line I—I of Fig. 2,

Fig. 2 is a view in cross section thereof on the line II—II of Fig. 1, and showing the application thereof to the commutator of an electric machine,

Fig. 3 is a side view of the contact members,

Fig. 4 is a plan view of one of the contact members, and

Fig. 5 is an enlarged side view of one of the pivotal members upon which the centrifugal members operate.

In the practice of my invention, I provide a stud plate 1, preferably in the form of a flanged disc or head, centered upon the shaft 2 of the machine. The machine is provided with a commutator cylinder 3

which is mounted upon a supporting core or spider 3^a. The head 1 is secured in spaced relation to the end of the commutator spider 3^a by means of a plurality of equidistantly spaced screws 4 upon which are fixedly mounted worm-studs or pivot members 5 having steep-threaded or spirally ribbed body portions 6 thereon, said worm-studs also serving as spacing means

between the stud plate 1 and the supporting spider 3^a of the commutator cylinder 3. 55

A weighted centrifugal member 7, having a properly threaded eccentric opening 8 and a weighted body or enlarged portion 9, is provided to operatively engage upon the threaded portion 6 of each stud member 5. 60

The centrifugal members 7 are maintained under suitable tension by means of three similar spiral tension springs 10, the weight members 7 being normally held in engagement with the commutator shaft 2 by the 65 tension of said springs 10. One end of each spring is connected to a pin 11 located at a certain distance from the operating center of one weight member and the other end of the spring is connected to a pin 12 located at a 70 greater effective distance from the operating center of the next weight member. Since the springs are connected thus alternately, each spring tends to move one of its associated weight members to the "in" position and the other to the "out" position, the resultant effect, however, being to hold all members in their "in" or normal position. 75

Loosely mounted for lateral movement on the worm-studs 5 and adjacent to the end of the commutator cylinder, is a follower plate or disc 13 having a flanged rim 14 thereabout. The follower plate 13 is normally held in spaced relation to the end of 80 the commutator by spiral compression springs 15 disposed upon the stud members 5. The follower plate 13 is provided, upon its inner face portion adjacent to the rim thereof, with a plurality of yieldable phosphor-bronze short-circuiting contactors 16 which are designed to have great resiliency and to provide a wiping action at the contact points, which is always desirable in securing good contact, especially when the 85 contacting surfaces become corroded, as when the motor is idle for long periods. As shown in Figs. 3 and 4, the contactors are arc-shaped pieces having their intermediate portions bent out, as at 17, but having cup-shaped central depressions 18 to provide two contact points 19 for each contactor. The flat terminals of the contactors are perforated and riveted to the follower plate as at 21. 90

In operation, at a predetermined speed of 100

rotation of the armature to which the device is applied, the centrifugal force on the weighted members 7 begins to exceed the net closing moment of the springs. The 5 weighted members immediately and rapidly rotate to their outermost positions against the rim of the stud plate 1, and in so rotating, travel axially also, by reason of the threads of the worm-studs 5 upon which 10 they are pivotally mounted. The follower plate 13 is thus caused to move toward the commutator, overcoming the opposition of the small compression springs 15, and bringing the yieldable contactors 16 into firm 15 engagement with the end of the commutator cylinder, thus short-circuiting the armature. Upon collapse of the centrifugal moment of the weight members 7, resulting 20 from the stopping of the motor, the springs restore the mechanism to the starting position.

During the above-described operation, the interlocking of the springs 10 with the weight members 7 compels all of said members to operate simultaneously in spite of the difference in either spring or weight moments. For example, if one of the three weight members here shown should have a greater centrifugal moment than the other two, and as a result, it should start to open in advance of the others, the action of the spring which tends to maintain this member 7 in a closed position and at the same time tends to effect an open position of an adjacent weight member connected thereto would be unduly stressed, retarding the motion of the first weight member and decreasing the resultant spring force tending to hold said adjacent weight member closed. 35 Again, the pull of the spring which tends to open the first-mentioned member and at the same time tends to close the adjacent third member will be decreased. Such action will also tend to retard the movement of 40 the first-mentioned member and to facilitate the operating of the third member.

While I have shown and described a certain embodiment of my invention, I desire that the disclosed embodiment shall be regarded as illustrative only, and that the appended claims shall be accorded the broadest construction consistent with the prior art.

I claim as my invention:

55 1. The combination with the commutator cylinder of a dynamo-electric machine, of a member spaced from and secured to the end thereof by a plurality of spaced threaded pivot members, a centrifugally actuated member pivotally and threadedly mounted on each of the threaded pivot members, and a short-circuiting member loosely disposed between said spaced member and said commutator cylinder, said centrifugally-actuated members adapted to pivot out-

wardly and simultaneously therewith to adjust themselves axially on their pivot members and force the short-circuiting member into engagement with the end of the commutator cylinder. 70

2. The combination with the commutator cylinder of a dynamo-electric machine, of a member spaced from, and secured to, the end thereof by a plurality of spaced pivot members, a centrifugally-actuated member 75 mounted on each of the pivot members, means yieldingly connecting said centrifugally-actuated members to one another, a short-circuiting member loosely disposed between said spaced member and said commutator cylinder and yielding means normally holding the short-circuiting member in spaced relation to the cylinder end, said centrifugally-actuated members adapted to pivot outwardly and simultaneously therewith to adjust themselves axially on their pivot members and force the short-circuiting member into engagement with the end of the commutator cylinder. 80

3. The combination with the commutator cylinder of an electric machine, of a plurality of steep-threaded pivot members fixedly connected thereto in spaced relation and extending from the end thereof, a centrifugally-actuated member correspondingly 95 threaded to, and mounted on, each of said pivot members, and a circuit-closing member slidably mounted on said pivot members, said centrifugally-actuated members adapted to be pivotally actuated outwardly 100 by centrifugal force and concurrently therewith to adjust themselves axially on said threaded members to move the circuit-closing member into engagement with the end of the commutator cylinder. 105

4. The combination with the commutator cylinder of an electric machine, of a plurality of steep-threaded pivot members fixedly attached thereto in spaced relation and extending from the end thereof, a centrifugally-actuated member correspondingly 110 threaded to, and mounted on, each of said pivot members, springs connecting said centrifugally-actuated members to one another, and a circuit-closing member slidably mounted on said pivot members, said centrifugally-actuated members adapted to be 115 pivotally actuated outwardly by centrifugal force and concurrently therewith to adjust themselves axially on said threaded members to move the circuit-closing member into engagement with the end of the commutator cylinder. 120

5. The combination with the commutator cylinder of an electric machine, of a plurality of spirally ribbed pivot members fixedly extending from the end thereof, a stop member secured to the outer ends thereof, a weighted centrifugally-actuated member 125 having a spirally ribbed opening therein 130

movably fitted on each of said pivot members, a plurality of springs connecting said centrifugally-actuated members to one another, and a short-circuiting member movably mounted on said pivot members adjacent to the end of the commutator cylinder and adapted to be moved into engagement with the end of the commutator cylinder by the action of said centrifugal members.

6 10 6. The combination with a commutator cylinder of an electric machine, of a plurality of spirally ribbed pivot members extending therefrom in spaced relation, a stop member secured to the outer ends thereof, a

15 15 weighted centrifugally-actuated member having a spirally-ribbed opening therein movably fitted on each of said ribbed pivot members, a plurality of springs connecting said centrifugally-actuated members to one

20 20 another, a follower member slidably mounted on said pivot members adjacent to said commutator cylinder, short-circuiting contacts carried by said follower member, and spring means for normally holding the contact carrying follower member out of short-circuiting engagement with said commutator cylinder, said centrifugally-actuated members being adapted to swing outwardly and simultaneously therewith to move axially on said ribbed pivot members to actuate the contact carrying follower member

25 30 into short-circuiting position.

7. A circuit making and breaking device comprising a substantially flat contact member and a relatively movable contactor member, the latter comprising a supporting member and a resilient contact member secured thereto at its two ends and having its intermediate portions bent out towards said substantially flat contact member, said outwardly bent intermediate portions having a cup-shaped central depression to provide two contact points for engaging said substantially flat contact member with a wiping action.

8. The combination with a substantially flat contact member comprising the smooth end surface of the commutator segments of a dynamo-electric machine, of an axially movable contactor member, the latter comprising a supporting member and a resilient contact member secured thereto at its two ends and having its intermediate portions bent out towards said substantially flat contact member, said outwardly bent intermediate portions having a cup-shaped central depression to provide two contact points for engaging said substantially flat contact member with a wiping action.

In testimony whereof, I have hereunto 60
subscribed my name this 9th day of October,
1923.

JOHN LYALL BROWN.
